TOWEL RACK

Guy Vrignaud, Grenoble, France, assignor to Allibert
Exploitation Societe Anonyme, Puteaux, France

Filed Nov. 6, 1974, Ser. No. 521,494

Term of patent 14 years

Int. Cl. D6—06

U.S. Cl. D6—99

FIG. 1 is a perspective view of a towel rack showing my new design;

FIG. 2 is a front elevational view thereof;

FIG. 3 is a rear elevational view thereof;

FIG. 4 is a bottom plan view thereof;

FIG. 5 is a top plan view thereof; and

FIG. 6 is an end elevational view thereof, the opposite end elevational view being identical.

I claim:

The ornamental design for a towel rack, as shown and described.
